UNITED STATES PATENT OFFICE

RALPH L. SKINNER, OF DETROIT, MICHIGAN

INTERNAL-COMBUSTION ENGINE

Application filed March 9, 1929, Serial No. 345,771. Renewed September 8, 1930.

My invention relates to structural and functional betterments in internal-combustion engines and concerns more particularly those having sliding valves, whereby to overcome difficulties heretofore existing in relation to sealing the gas pressures in the cylinders and thereby preventing substantial or objectionable leakage.

To permit those trained in this art to fully understand the invention, in the accompanying drawings forming a part of this specification, a present desirable and preferred embodiment of the invention has been illustrated in detail, and, for simplicity, like reference characters have been used throughout the several views to designate the same parts.

In these drawings:

Figure 1 is a substantially central, longitudinal section on line 1-1 of Figure 3 through one cylinder of a multi-cylinder engine;

Figure 2 is an enlarged horizontal section on line 2-2 of Figure 1;

Figure 3 is a similar section on line 3-3 of Figure 1; and

Figure 4 is a fragmentary longitudinal section through a portion of one of the engine cylinders and associated parts.

By reference to these drawings, it will be noted that the engine includes an outer, water-cooled cylinder 11 mounted on the top of a crank-case 12 containing the usual supply of lubricating oil.

Inside of such outer cylinder, concentric therewith and spaced inwardly away from such exterior cylinder, an inner cylinder 13 is mounted being supported solely from its lower end by means of screws 14, 14 taking into threaded holes in the lower part of the cylinder-block.

Cylinder 11 has inlet and exhaust ports 15 and 16, respectively, and the flat, top edge 17 of the inner cylinder, which is at right-angles to its axis, is located below such ports, as is clearly indicated in Figures 1 and 4.

Bearing on such top edge of the inner cylinder is a split, expansible, sealing-ring 18 having admission and discharge ports 19

and 21, respectively, in substantial register with the corresponding cylinder-ports 15 and 16, the split or slip joint 22 of such ring having outer and inner overlapping tongues 23 and 24 which seal the joint effectively especially when forced outwardly by the gas pressure in the cylinder and without preventing the proper and effective expansion or enlargement of the ring.

Cylinder-port 15 and the companion port of the inlet-valve, hereinafter referred to, have registering bridges 25 and 26 and the ring-joint 22 is maintained in register with these by a radial, holding pin 27 fixedly mounted in a cylinder-head 28 bolted on and depending into the upper part of the outer cylinder, the end of such pin fitting in a cavity in the inner face of the ring.

An endless, hold-down ring 29 of right-angle cross-section, giving it a shallow, inner, horizontal flange or ledge 31, bears on the upper edge of the sealing-ring, their contacting faces being at right-angles to their common axis, so that the sealing-ring may contract and expand without material interference.

The lower, reduced-diameter section of the cylinder-head 28 is supplied externally with any suitable number of ring-grooves 32, 32 accommodating split expansion-rings 33, 33, similar to the customary piston-rings, pressing outwardly by their own inherent resiliency against the inner face of the hold-down ring 29 to prevent the gas pressures of compression and explosion from leaking out between them.

An annular cavity 34 in the cylinder-head provides space for a pair of semi-circular ring-sections 35 and 36, each having an external-shoulder 37 overlying and bearing on the top edge of the hold-down ring 29, as is perhaps more clearly depicted in Figure 4.

Ring-section 35 is in substantial alignment or register with the inlet-port 19 and the correlated ring-section 36 is in similar relation to the exhaust-port 21, member 35 in its upper face, in the present instance, having eleven, equally-spaced recesses 38, each housing a short, coiled spring 39 pressing at its upper end against the top wall 100.

of cylinder-head cavity 34 and bearing at its lower end against the bottom wall of its recess, the associated element 36 having twenty such recesses 41 and their springs 42.

5 Thus the sealing-ring, 18 due to the hold-down ring, has a less downward pressure against the top end of the inner cylinder at the inlet-ports than it has at the exhaust ports by reason of the difference in the number of springs employed, although it will be apparent that an analogous result could be accomplished by using the same number of springs in each instance with those at the exhaust-ports of greater strength than those 10 at the inlet-ports:

Ported, transversely-curved or arcuate inlet and exhaust valves 43 and 44, respectively, reciprocate in the aligned, thin, annular chambers between the two cylinders 20 and between the outer cylinder and the cylinder-head, being actuated in proper timed relation by suitably-rotated crank-shafts or eccentrics 45 and 46 in the crank-case and their associated connecting-rods 47 and 48.

25 By means not necessary to describe, such valves are suitably lubricated with the excess lubricant withdrawn to prevent its finding access into the ports, manifolds, or cylinders.

30 The usual piston 49 reciprocates in the inner cylinder and it is joined in the customary manner to the main crank-shaft, not shown, by the connecting-rod 51.

35 The new structure operates practically as follows:

The natural tendency of the sealing-ring to expand enlarges it and presses it outwardly against the valves and forces the latter against the inner surface of the exterior cylinder, and this action is augmented by the varying gas pressures in the cylinder, whereby such pressures of compression and explosion contribute to sealing themselves in the cylinder by preventing leakage 40 at the joint of the sealing-ring and between the ring and valves, and between the latter and the outer cylinder.

45 It is also necessary to press the sealing-ring down sufficiently on to the top end of the inner cylinder to preclude leakage at this point.

This is accomplished in part by the gas pressures in the cylinder pressing downwardly on the ledge or flange 31 of the hold-down ring and in part by the plurality of springs 39 and 42 which, through the ring-sections 35 and 36, bear downwardly on the hold-down ring.

50 Such action not only excludes leakage between the ported sealing-ring and inner cylinder but also between the hold-down and sealing rings.

55 When the maximum explosion pressure occurs, the exhaust-valve 44 is moving upwardly tending to lift the sealing-ring with

it off of its seat on the end of the inner cylinder and at the same time the inlet or admission valve is traveling downwardly and tends to hold the sealing-ring on its seat on the end of the inner cylinder.

70 It is in part to compensate for such differences in forces acting on opposite portions of the sealing-ring that the ring 35-36 is divided into sections with the one corresponding to the exhaust valve and port having a greater downward spring action than the companion one, so that when the explosion occurs, the forces acting on the sealing-ring will be substantially equalized around it, thus allowing the ring itself to 75 expand more easily and efficiently.

80 When there is no substantial pressure in the cylinder, the springs prevent the sealing-ring from rising from its bearing on the inner cylinder due to the movements of the valves against which it presses.

85 It will, therefore, be readily understood that the fluid pressures in the cylinder are employed to assist in sealing the structural elements in such a way as to prevent escape 90 of the gases or the reduction of the pressures.

95 It will, furthermore, be comprehended that the gas pressures in the cylinder cannot reach the springs which act on the hold-down ring, so that such springs do not have to counteract such pressures, to do their intended work.

100 By the simple means illustrated and described, the sealing-ring and its affiliated mechanical elements hold the pressures in the cylinder without material loss, using such pressures to aid in the sealing action and employing such other means as may be suitable to assist in attaining the desired 105 result.

110 The invention is obviously not limited and restricted to the precise and exact details of structure presented and these may be modified within comparatively wide limits without departure from the heart and essence of the invention and without the loss of any of its material or substantial benefits or advantages.

115 Some of the features of construction of this appliance are covered by the claims of my co-pending patent application, Serial No. 337,778, filed February 6th, 1929.

I claim:

120 1. In an internal-combustion engine, the combination of an outer cylinder having inlet and exhaust ports, an inner cylinder spaced inwardly away from said outer cylinder, means to seal the gas pressures in the engine against leakage including an expandable sealing-ring bearing edgewise on said inner cylinder and having ports in substantial register with said cylinder ports, a head for said outer-cylinder, ported arcuate valves between said outer cylinder and said 125 130

- inner cylinder and sealing-ring and movable longitudinally of said cylinders, means to reciprocate said valves, a reciprocatory piston in said inner-cylinder, a connecting-rod joined to said piston and adapted for connection to a crank-shaft, and means to allow the gas pressures above said piston to press said sealing-ring down on its seat on said inner cylinder. 5 70
2. In an internal-combustion engine, the combination of an outer cylinder having inlet and exhaust ports, an inner cylinder spaced inwardly away from said outer cylinder, means to seal the gas pressures in the engine against leakage including an expansible sealing-ring bearing edgewise on said inner cylinder and having ports in substantial register with said cylinder ports, a head for said outer-cylinder, ported arcuate valves between said outer cylinder and said inner cylinder and sealing-ring and movable longitudinally of said cylinders, means to reciprocate said valves, a reciprocatory piston in said inner-cylinder, a connecting-rod joined to said piston and adapted for connection to a crank-shaft, means to allow the gas pressures above said piston to press said sealing-ring down on to its seat on said inner cylinder, and resilient means supplementing such sealing-ring pressing action of the gas. 10 15 20 25 30 35 40 45 50 55 60 65 70 75 80 85 90 95 100 105 110 115 120 125
3. In an internal-combustion engine, the combination of an outer cylinder having inlet and exhaust ports, an inner cylinder spaced inwardly away from said outer cylinder, means to seal the gas pressures in the engine against leakage including an expansible sealing-ring bearing edgewise on said inner cylinder and having ports in substantial register with said cylinder ports, a head for said outer-cylinder, ported arcuate valves between said outer cylinder and said inner cylinder and sealing-ring and movable longitudinally of said cylinders, means to reciprocate said valves, a reciprocatory piston in said inner-cylinder, a connecting-rod joined to said piston and adapted for connection to a crank-shaft, means to allow the gas pressures above said piston to press said sealing-ring down on to its seat on said inner cylinder, resilient means supplementing such sealing-ring pressing action of the gas, and means to prevent access of said gas pressures to said resilient means. 13 18 23 28 33 38 43 48 53 58 63 68 73 78 83 88 93 98 103 108 113 118 123
4. In an internal-combustion engine, the combination of an outer cylinder having inlet and exhaust ports, an inner cylinder spaced inwardly away from said outer cylinder, means to seal the gas pressures in the engine against leakage including an expansible sealing-ring bearing edgewise on said inner cylinder and having ports in substantial register with said cylinder ports, a head for said outer-cylinder, ported arcuate valves between said outer cylinder and said inner cylinder and sealing-ring and movable longitudinally of said cylinders, means to reciprocate said valves, a reciprocatory piston in said inner-cylinder, a connecting-rod joined to said piston and adapted for connection to a crank-shaft, and means to apply unequal pressures simultaneously on different portions of said sealing-ring tending to force it to its seat on said inner cylinder. 14 19 24 29 34 39 44 49 54 59 64 69 74 79 84 89 94 99 104 109 114 119 124
5. In an internal-combustion engine, the combination of an outer cylinder having inlet and exhaust ports, an inner cylinder spaced inwardly away from said outer cylinder, an expansible sealing-ring bearing edgewise on said inner cylinder and having ports in substantial register with said cylinder ports, a head for said outer-cylinder, ported arcuate valves between said outer cylinder and said inner cylinder and sealing-ring and movable longitudinally of said cylinders, means to reciprocate said valves, a reciprocatory piston in said inner-cylinder, a connecting-rod joined to said piston and adapted for connection to a crank-shaft, and a hold-down ring bearing on the upper face of said sealing-ring and having a transverse surface exposed to the gas pressures above said piston, whereby such pressures tend to hold said sealing-ring to its seat on said inner cylinder. 15 20 25 30 35 40 45 50 55 60 65 70 75 80 85 90 95 100 105 110 115 120 125
6. In an internal-combustion engine, the combination of an outer cylinder having inlet and exhaust ports, an inner cylinder spaced inwardly away from said outer cylinder, means to seal the gas pressures in the engine against leakage including an expansible sealing-ring bearing edgewise on said inner cylinder and having ports in substantial register with said cylinder ports, a head for said outer-cylinder, ported arcuate valves between said outer cylinder and said inner cylinder and sealing-ring and movable longitudinally of said cylinders, means to reciprocate said valves, a reciprocatory piston in said inner-cylinder, a connecting-rod joined to said piston and adapted for connection to a crank-shaft, and means to apply unequal pressures simultaneously on different portions of said sealing-ring tending to force it to its seat on said inner cylinder. 16 21 26 31 36 41 46 51 56 61 66 71 76 81 86 91 96 101 106 111 116 121
7. In an internal-combustion engine, the combination of an outer cylinder having inlet and exhaust ports, an inner cylinder spaced inwardly away from said outer cylinder, means to seal the gas pressures in the engine against leakage including an expansible sealing-ring bearing edgewise on

said inner cylinder and having ports in substantial register with said cylinder ports, a head for said outer-cylinder, ported arcuate valves between said outer cylinder and said inner cylinder and sealing-ring and movable longitudinally of said cylinder, means to reciprocate said valves, a reciprocatory piston in said inner-cylinder, a connecting-rod joined to said piston and adapted for connection to a crank-shaft, means to allow the gas pressures above said piston to press said sealing-ring down on its seat on said inner cylinder, and resilient means to apply unequal pressures simultaneously on different portions of said sealing-ring tending to force it to its seat on said inner cylinder.

8. In an internal-combustion engine, the combination of an outer cylinder having inlet and exhaust ports, an inner cylinder spaced inwardly away from said outer cylinder, means to seal the gas pressures in the engine against leakage including an expansible sealing-ring bearing edgewise on said inner cylinder and having ports in substantial register with said cylinder ports, a head for said outer-cylinder, ported arcuate valves between said outer cylinder and said inner cylinder and sealing-ring and movable longitudinally of said cylinders, means to reciprocate said valves, a reciprocatory piston in said inner-cylinder, a connecting-rod joined to said piston and adapted for connection to a crank-shaft, resilient means to apply unequal pressures simultaneously on different portions of said sealing-ring tending to force it to its seat on said inner cylinder, and means to prevent access of the gas pressures above said piston to said resilient means.

40 9. In an internal-combustion engine, the combination of an outer cylinder having inlet and exhaust ports, an inner cylinder spaced inwardly away from said outer cylinder, means to seal the gas pressures in the engine against leakage including an expansible sealing-ring bearing edgewise on said inner cylinder and having ports in substantial register with said cylinder ports, a head for said outer-cylinder, ported arcuate valves between said outer cylinder and said inner cylinder and sealing-ring and movable longitudinally of said cylinders, means to reciprocate said valves, a reciprocatory piston in said inner-cylinder, a connecting-rod joined to said piston and adapted for connection to a crank-shaft, a hold-down ring bearing on said sealing-ring, and resilient means to apply unequal pressures simultaneously on different portions of said hold-down ring to force said hold-down ring to its bearing on said sealing-ring and said sealing-ring to its seat on said inner cylinder.

65 10. In an internal-combustion engine, the combination of an outer cylinder having in-

let and exhaust ports, an inner cylinder spaced inwardly away from said outer cylinder, means to seal the gas pressures in the engine against leakage including an expansible sealing-ring bearing edgewise on said inner cylinder and having ports in substantial register with said cylinder ports, a head for said outer-cylinder, ported arcuate valves between said outer cylinder and said inner cylinder and sealing-ring and movable longitudinal of said cylinders, means to reciprocate said valves, a reciprocatory piston in said inner-cylinder, a connecting-rod joined to said piston and adapted for connection to a crank-shaft, a hold-down ring bearing on said sealing-ring, means to apply unequal pressures simultaneously on different portions of said hold-down ring to force said hold-down to its bearing on said sealing-ring and said sealing-ring to its seat on said inner cylinder, and means to prevent access of the gas pressures above said piston to said unequal pressure means.

11. In an internal-combustion engine, the combination of an outer cylinder having inlet and exhaust ports, an inner cylinder spaced inwardly away from said outer cylinder, an expansible sealing-ring bearing edgewise on said inner cylinder and having ports in substantial register with said cylinder ports, a head for said outer-cylinder, ported arcuate valves between said outer cylinder and said inner cylinder and sealing-ring and movable longitudinally of said cylinders, means to reciprocate said valves, a reciprocatory piston in said inner-cylinder, a connecting-rod joined to said piston and adapted for connection to a crank-shaft, a hold-down ring bearing on the upper edge of said sealing-ring, expansion ring means between said cylinder-head and said hold-down ring preventing leakage of gas pressures above said piston therebetween, a ring in sections bearing on said hold-down ring, and resilient means interposed between said cylinder-head and each of said ring sections pressing the latter downwardly on said hold-down ring and the latter down on said sealing-ring.

12. In an internal-combustion engine, the combination of an outer cylinder having inlet and exhaust ports, an inner cylinder spaced inwardly away from said outer cylinder, an expansible sealing-ring bearing edgewise on said inner cylinder and having ports in substantial register with said cylinder ports, a head for said outer-cylinder, ported arcuate valves between said outer cylinder and said inner cylinder and sealing-ring and movable longitudinally of said cylinders, means to reciprocate said valves, a reciprocatory piston in said inner-cylinder, a connecting-rod joined to said piston and adapted for connection to a crank-shaft, an endless hold-down ring bearing on the upper

edge of said sealing-ring, expansion ring means between said cylinder-head and said hold-down ring preventing leakage of gas pressures above said piston therebetween, a ring in sections bearing on said hold-down ring, and a plurality of springs interposed between said cylinder-head and each of said ring sections pressing the latter downwardly on said hold-down ring and the latter down on said sealing-ring.

13. In an internal-combustion engine, the combination of an outer cylinder having inlet and exhaust ports, an inner cylinder spaced inwardly away from said outer cylinder, an expansible sealing-ring bearing edgewise on said inner cylinder and having ports in substantial register with said cylinder ports, a head for said outer-cylinder, ported arcuate valves between said outer cylinder and said inner cylinder and sealing-ring and movable longitudinally of said cylinders, means to reciprocate said valves, a reciprocatory piston in said inner-cylinder, a connecting-rod joined to said piston and adapted for connection to a crank-shaft, an endless hold-down ring bearing on the upper edge of said sealing-ring, expansion ring means between said cylinder-head and said hold-down ring preventing leakage of gas pressures above said piston therebetween, a ring in sections bearing on said hold-down ring, and resilient means of unequal strengths interposed between said cylinder-head and said ring sections pressing the latter downwardly on said hold-down ring and the latter down on said sealing-ring.

14. In an internal-combustion engine, the combination of an outer cylinder having inlet and exhaust ports, an inner cylinder spaced inwardly away from said outer cylinder, an expansible sealing-ring bearing edgewise on said inner cylinder and having ports in substantial register with said cylinder ports, a head for said outer-cylinder, ported arcuate valves between said outer cylinder and said inner cylinder and sealing-ring and movable longitudinally of said cylinders, means to reciprocate said valves, a reciprocatory piston in said inner-cylinder, a connecting-rod joined to said piston and adapted for connection to a crank-shaft, an endless hold-down ring bearing on the upper edge of said sealing-ring, expansion ring means between said cylinder-head and said hold-down ring preventing leakage of gas pressures above said piston therebetween, a ring divided into two sections bearing on said hold-down ring in substantial register with the inlet and exhaust ports of said sealing-ring, resilient means interposed between said cylinder-head and said inlet-port ring section, and resilient means of greater strength interposed between said cylinder-head and said exhaust-port ring section, said resilient means pressing said ring sections

downwardly on said hold-down ring and the latter down on said sealing-ring.

15. In an internal-combustion engine, the combination of a ported outer cylinder, an inner cylinder in and spaced inwardly away from said outer cylinder, means to seal the gas pressures in the engine against leakage including an expansible sealing-ring bearing edgewise on said inner cylinder and having port means in substantial register with the port means of said outer cylinder, a head for said outer cylinder, arcuate valve-means between said outer cylinder and said inner cylinder and sealing-ring and movable longitudinally of said cylinders and controlling the port means of said cylinder and ring, means to reciprocate said valve-means, a reciprocatory piston in said inner cylinder, a connecting-rod joined to said piston and adapted for connection to a crank-shaft, and means to allow the gas pressures above said piston to press said sealing-ring toward its seat on said inner cylinder.

16. In an internal-combustion engine, the combination of a ported outer cylinder, an inner cylinder in and spaced inwardly away from said outer cylinder, means to seal the gas pressures in the engine against leakage including an expansible sealing-ring bearing edgewise on said inner cylinder and having port means in substantial register with the port means of said outer cylinder, a head for said outer cylinder, arcuate valve-means between said outer cylinder and said inner cylinder and sealing-ring and movable longitudinally of said cylinders and controlling the port means of said cylinder and ring, means to reciprocate said valve-means, a reciprocatory piston in said inner cylinder, a connecting-rod joined to said piston and adapted for connection to a crank-shaft, means to allow the gas pressures above said piston to press said sealing-ring toward its seat on said inner cylinder, and resilient means supplementing such sealing-ring pressing action of the gas.

17. In an internal-combustion engine, the combination of a ported outer cylinder, an inner cylinder in and spaced inwardly away from said outer cylinder, means to seal the gas pressures in the engine against leakage including an expansible sealing-ring bearing edgewise on said inner cylinder and having port means in substantial register with the port means of said outer cylinder, a head for said outer cylinder, arcuate valve-means between said outer cylinder and said inner cylinder and sealing-ring and movable longitudinally of said cylinders and controlling the port means of said cylinder and ring, means to reciprocate said valve-means, a reciprocatory piston in said inner cylinder, a connecting-rod joined to said piston and adapted for connection to a crank-shaft, means to allow the gas pressures above said

piston to press said sealing-ring toward its seat on said inner cylinder, resilient means supplementing such sealing-ring pressing action of the gas, and means to prevent access of said gas pressures to said resilient means.

18. In an internal-combustion engine, the combination of a ported outer cylinder, an inner cylinder in and spaced inwardly away from said outer cylinder, means to seal the gas pressures in the engine against leakage including an expansible sealing-ring bearing edgewise on said inner cylinder and having port means in substantial register with the port means of said outer cylinder, a head for said outer cylinder, arcuate valve-means between said outer cylinder and said inner cylinder and sealing-ring and movable longitudinally of said cylinders and controlling the port means of said cylinder and ring, means to reciprocate said valve-means, a reciprocatory piston in said inner cylinder, a connecting-rod joined to said piston and adapted for connection to a crank-shaft, a hold-down ring bearing on the upper part of said sealing-ring and having a transverse surface exposed to the gas pressures above said piston, whereby such pressures tend to hold said hold-down ring to its bearing on said sealing-ring and said sealing-ring to its seat on said inner cylinder.

19. In an internal-combustion engine, the combination of a ported outer cylinder, an inner cylinder in and spaced inwardly away from said outer cylinder, an expansible sealing-ring bearing edgewise on said inner cylinder and having port means in substantial register with the port means of said outer cylinder, a head for said outer cylinder, arcuate valve-means between said outer cylinder and said inner cylinder and sealing-ring and movable longitudinally of said cylinders and controlling the port means of said cylinder and ring, means to reciprocate said valve-means, a reciprocatory piston in said inner cylinder, a connecting-rod joined to said piston and adapted for connection to a crank-shaft, an endless hold-down ring bearing on the upper part of said sealing-ring and having a transverse surface exposed to the gas pressures above said piston, whereby such pressures tend to hold said hold-down ring to its bearing on said sealing-ring and said sealing-ring to its seat on said inner cylinder, and means to prevent escape of said gas pressures between said cylinder-head and said hold-down ring.

20. In an internal-combustion engine, the combination of a ported outer cylinder, an inner cylinder in and spaced inwardly away from said outer cylinder, an expansible sealing-ring bearing edgewise on said inner cylinder and having port means in substantial register with the port means of said outer cylinder, a head for said outer cylinder, ar-

cuate valve-means between said outer cylinder and said inner cylinder and sealing-ring and movable longitudinally of said cylinders and controlling the port means of said cylinder and ring, means to reciprocate said valve-means, a reciprocatory piston in said inner cylinder, a connecting-rod joined to said piston and adapted for connection to a crank-shaft, a hold-down ring bearing on the upper part of said sealing-ring and having a transverse surface exposed to the gas pressures above said piston, whereby such pressures tend to hold said hold-down ring to its bearing on said sealing-ring and said sealing-ring to its seat on said inner cylinder, and resilient means acting on said hold-down ring tending to force said hold-down ring to its bearing on said sealing-ring and said sealing-ring to its seat on said inner cylinder.

21. In an internal-combustion engine, the combination of a ported outer cylinder, an inner cylinder in and spaced inwardly away from said outer cylinder, means to seal the gas pressures in the engine against leakage including an expansible sealing-ring bearing edgewise on said inner cylinder and having port means in substantial register with the port means of said outer cylinder, a head for said outer cylinder, arcuate valve-means between said outer cylinder and said inner cylinder and sealing-ring and movable longitudinally of said cylinders and controlling the port means of said cylinder and ring, means to reciprocate said valve-means, a reciprocatory piston in said inner cylinder, a connecting-rod joined to said piston and adapted for connection to a crank-shaft, and means pressing said sealing-ring to its seat on said inner cylinder with unequal pressures simultaneously acting on different sections of such sealing-ring.

In witness whereof I have hereunto set my hand.

RALPH L. SKINNER.
